FIG. 1 is a perspective view of an accessory for the installa-
tion, positioning and clamping of scope in an air rifle showing
my new design;

FIG. 2 shows the accessory of FIG. 1 when positioned with a
scope and a portion of a rifle shown in broken lines; and,
FIG. 3 is an end view of the accessory of FIG. 1.

The broken line showing in FIG. 2 is for the purpose of
illustrating the environment of the article only and forms no
part of the claimed design.
